25 Claims

ABSTRACT OF THE DISCLOSURE

Toilet bars having improved after-wash feel properties comprise at least 15% by weight of polyethyleneoxide quaternary ammonium compounds. The latter must have at least three ethyleneoxide units in a chain and satisfy an expression relating the number of ethyleneoxide units to the number of carbon atoms and the number of quaternary nitrogen atoms.

This application is a continuation of application Ser. No. 60,781, filed July 30, 1970, now abandoned, which application was a continuation-in-part of our application Ser. No. 835,739, filed June 23, 1969, also now abandoned.

The invention relates to a toilet bar, more particularly it relates to a toilet bar with improved properties.

Toilet bars are a very old and well-established form of detergent product. The quality of toilet bars has been gradually increasing and the modern toilet bar represents a considerable technical development. Toilet bars are still mainly based on soaps but in recent years there has been an increasing interest in the use of other detergents.

Despite these advances the search for improvements for toilet bars still continues. In particular it has long been recognised that there is a conflict between the detergent and the cosmetic action of toilet bars. For instance, after washing with a toilet bar the skin often feels "de-oiled." Skin with this after-wash feel is often described as dry. It is an object of the present invention to mitigate this after-wash feel and related effects at reasonable cost.

According to the present invention it has surprisingly been found that if a toilet bar contains at least 15% by weight of a polyethyleneoxide quaternary ammonium compounds with certain characteristics given hereafter, after-wash feel and related effects are improved; the skin feels more pleasant and smoother. The characteristics required of the polyethyleneoxide quaternary ammonium compounds used in the toilet bars of the present invention are that they must contain a polyethyleneoxide group containing at least three ethyleneoxide units in a straight chain (i.e. —CH₂CH₂OCH₂CH₂OCH₂CH₂O—). The term "polyethylene-oxide quaternary ammonium compounds" used hereinafter refers to compounds with such polyethylene oxide groups.

Bars containing quaternary ammonium compounds have been disclosed earlier, for instance in UK patent specifications Nos. 443,795, 737,898 and 759,837. Also a bar containing a minor amount of a quaternary ammonium compound containing a polyethyleneoxide group is disclosed in UK patent specification No. 1,027,898. But the surprising improved after-wash feel and related effects obtained by bars according to the present invention are neither disclosed nor envisaged.

The preferred polyethyleneoxide quaternary ammonium compounds have a K value of from 3 to 0.01 when the

2

compound is detergents and from 30 to 0.67 when the compound is non-detergents, the K value being defined by the expression:

$$K = \frac{\Sigma (EO)}{\Sigma C \times \Sigma \overset{\dagger}{N}}$$

where $\Sigma (EO)$ is the total number of ethyleneoxide units, ΣC is the total number of carbon atoms not in ethyleneoxide units and

$$\Sigma \overset{\dagger}{N}$$

is the total number of quaternary nitrogen atoms per repeating unit of the compound. Most polyethyleneoxide compounds do not have repeating units, in which case the values of

$$\Sigma (EO), \Sigma C \text{ and } \Sigma \overset{\dagger}{N}$$

20 apply to the compounds as a whole, but certain polyethyleneoxide compounds are polymeric or may be regarded as dimers, in which case the values of

$$\Sigma (EO), \Sigma C \text{ and } \Sigma \overset{\dagger}{N}$$

25 are derived from each repeating unit. The K value is a function of the hydrophobic/hydrophilic balance of a compound.

A toilet bar containing at least 15% by weight of a 30 polyethyleneoxide quaternary ammonium compound having a K value within these limits displays improved after-wash feel properties.

In a polyethyleneoxide quaternary ammonium compound having the formula

for use in a bar according to the invention the nature of the groups R₁, R₂, R₃ and R₄ can vary very widely. But 40 R₁, R₂, R₃ or R₄ may not be hydrogen atoms since such compounds are better classified as salts of ternary ammonium compounds rather than as quaternary ammonium compounds. Compounds are also excluded in which any of the groups R₁, R₂, R₃ and R₄ contains an anionic group. 45 Such compounds are better described as betaines than as quaternary ammonium compounds since the anionic group destroys their quaternary nature. The groups R₁, R₂, R₃ and R₄ can be straight-chain, branched-chain or cyclic alkyl; aryl; alkaryl; aralkyl; or heterocyclic groups, and 50 amongst the many substituent groups or linkages that can be present are ethylenic and acetylenic linkages, conjugated or otherwise, carbonyl, ester and amide groups and linkages, and halogen and nitro groups. Also two or more of the groups R₁, R₂, R₃ and R₄ can form a heterocyclic ring with the quaternary nitrogen atom. At least one of the groups, R₁, R₂, R₃ and R₄ must comprise a polyethyleneoxide group containing at least three ethyleneoxide units, which may but need not be directly attached to the quaternary nitrogen atom.

60 It will be appreciated that one or more of the groups R₁, R₂, R₃ and R₄ may also be linked to one or more further quaternary nitrogen atoms, each with its own substituent groups R₁, R₂, R₃ and R₄.

65 For convenience, the term "compatible quaternary nitrogen substituent group" is used hereinafter to cover all the types of group R₁, R₂, R₃ and R₄ which can satisfactorily be used, as described above.

70 Any compatible anion X[—] can be used with the quaternary ammonium compound. Preferred anions are monovalent, particularly the halides, i.e. chloride, bromide and iodide, but other anions which can be used include, for example, sulphate, phosphate and acetate anions.

The necessary range for the K value as defined hereinbefore depends on whether the polyethyleneoxide quaternary ammonium compound is detergents or not. In general, it has been found that if a polyethyleneoxide quaternary ammonium compound contains a straight-chain of more than six carbon atoms, or an aralkyl or alkaryl group containing more than eight carbon atoms, the polyethyleneoxide quaternary ammonium compound is detergents. Thus, for example, polyethyleneoxide quaternary ammonium compounds of the general formula:

where $a+b+c$ is 9 or 27 and R is benzyl or ethyl are non-detergents.

The term EO is used herein to designate the group $-\text{CH}_2\text{CH}_2\text{O}-$ or, when terminal, the group

When the term is preceded by a number with a bar above, e.g. $\bar{14}$, this means that the product concerned contains *on average* the number of EO groups indicated, that is fourteen in the example. This terminology is used since polyethyleneoxide products are usually made by condensation of a compound containing a reactive hydrogen atom with ethyleneoxide, e.g. in the case of an alcohol the reaction is:

The product obtained is inevitably a mixture, containing, for example, some R.O.12 EO and some R.O. 16 EO but on average it contains fourteen EO units.

Whilst a polyethyleneoxide quaternary ammonium compound for use in a bar according to the invention must, as specified above, contain at least one group with 3 EO units, it has been found that the preferred polyethyleneoxide quaternary ammonium compounds contain at least one 5 EO group.

The extent to which a bar according to the invention displays improved after-wash feel is particularly surprising when considering the extent of the effect with toilet bars containing a quaternary ammonium compound not containing a polyethyleneoxide group.

Presence in a quaternary ammonium compound of a polyethylene-oxide group increases water-solubility and would be expected to reduce any skin effect, see for instance B. Idson, J. Soc. Cosmetic Chemists, 1967, 18, 91, particularly at page 99, last paragraph. It is therefore surprising that bars according to the invention give at least comparable after-wash feel properties to bars containing quaternary ammonium compounds not having polyethyleneoxide groups. This is particularly important since polyethyleneoxide quaternary ammonium compounds are potentially cheaper than quaternary ammonium compounds not containing polyethyleneoxide groups.

It will be appreciated that if a polyethyleneoxide quaternary ammonium compound showing little or no detergents activity is used in a bar according to the invention a detergents compound or compounds must also be included in the bar. Detergents compounds can also be used, if desired, with polyethyleneoxide quaternary ammonium compounds that are detergents. Suitable detergents compounds for such use include other quaternary ammonium compounds, either containing a polyethyleneoxide group or not, zwitterionic compounds, amphoteric compounds, anionic compounds and nonionic compounds.

It has surprisingly been found that some bars according to the invention display a number of other effects related to after-wash feel. These are mildness to the skin, moisturisation of the skin and protection of the skin against "insult" by anionic detergents.

Thus some polyethyleneoxide quaternary ammonium

compounds have been found to be surprisingly mild to the skin. For instance, as shown in Example 203 hereinafter, certain polyethyleneoxide quaternary ammonium compounds are milder than related compounds not containing a polyethyleneoxide group. Thus, for example, compounds of the general formulae

where R is a C_8 to C_{18} straight-chain alkyl group or a C_8 to C_{18} straight-chain alkyl group interrupted by a phenylene group, and X^- is a halide ion, have been found to be less mild than the same compounds where one or two methyl groups have been replaced by polyethyleneoxide groups.

15 Therefore, in a preferred toilet bar according to the invention the polyethyleneoxide quaternary ammonium compound has the formula

20 where R_1 is a C_8 to C_{18} straight-chain alkyl group or a C_8 to C_{18} straight-chain alkyl group interrupted by a phenylene group; R_2 is a methyl or benzyl group and R_3 is methyl or $(\text{EO})_n$, and n is at least 3.

Detergents compositions are often expected to clean heavily-soiled clothes or dishes, often in very mild conditions, for instance at low temperatures and concentrations. Often compositions formulated to perform well in such conditions can be too powerful undiluted to be allowed to come into contact with sensitive skin without causing unpleasant, if minor, effects. Nevertheless, such contact, particularly with dishwashing liquids, can occur in practice. It has been found that use of some bars according to the invention surprisingly mitigates the effects of contact with such compositions.

35 The presence of polyethyleneoxide groups is believed to reduce the germicidal activity of quaternary ammonium compounds, which compounds in general contain at least one C_8 to C_{18} straight-chain alkyl group. However, it has 40 been found that if the polyethyleneoxide quaternary ammonium compound does not contain more than 40 ethyleneoxide units per quaternary nitrogen atom the compound has adequate germicidal activity, provided that the analogous compound without polyethyleneoxide groups, i.e. with such groups replaced by methyl groups, has 45 germicidal activity. A toilet bar with effective germicidal properties is obtained particularly if the bar contains a major proportion, that is more than 50% by weight, of such a polyethyleneoxide quaternary ammonium compound.

50 It should be noted that the present invention is applicable to all toilet bars comprising at least 15% by weight of a polyethyleneoxide quaternary ammonium compound as herein defined, which gives surprising improved after-wash feel and related effects. Nevertheless, the invention 55 has two principal aspects, namely, a toilet bar comprising a major proportion of a polyethyleneoxide quaternary ammonium compound on which it depends for its detergents properties, and a toilet bar based on an anionic detergents compound and containing from 15 to 35%, preferably from 20 to 30% by weight, of a polyethyleneoxide quaternary ammonium compound.

60 It is a particularly significant feature of the invention that it has been found that polyethyleneoxide quaternary ammonium compounds are surprisingly compatible with anionic detergents compounds. Quaternary ammonium compounds often form complexes with anionic detergents compounds, which complexes often separate out with consequent loss of detergents action. It has been found 65 that polyethyleneoxide quaternary ammonium compounds are surprisingly less likely to form complexes that separate out than are other quaternary ammonium compounds.

70 Also it has surprisingly been found that bars according to the invention based on anionic detergents compounds give a better after-wash feel than do bars based on anionic

detergent compounds containing analogous quaternary ammonium compounds.

Thus, a particular aspect of the invention is a toilet bar based on an anionic detergent compound and containing from 15 to 35%, preferably from 20 to 30%, by weight of a polyethyleneoxide quaternary ammonium compound.

It has further been found that polyethyleneoxide quaternary ammonium compounds are surprisingly good at dispersing lime soap, that is the insoluble soap normally formed as a scum when soap-bars are used in hard water. A particular feature of the invention is therefore a toilet bar based on soap, usually a sodium soap of C₁₂ to C₂₂ fatty acids, and containing from 15 to 35%, preferably from 20 to 30%, by weight of a polyethyleneoxide quaternary ammonium compound.

The preparation of toilet bars based on an anionic non-ionic or zwitterionic detergent compound and containing from 15 to 35% by weight of a polyethyleneoxide quaternary ammonium compound is achieved by the standard techniques normally used for formulating bars based on anionic, nonionic or zwitterionic detergent compounds. In general, these involve either casting, pressure moulding or plodding and stamping. However, with the inclusion of the polyethylene oxide quaternary ammonium compounds in the bars according to the present invention, it may be necessary to adapt the compositions by, for example, incorporating therein plasticisers, lather improvers and hardening agents, etc.

The formulation of bars with adequate physico-chemical properties from a polyethyleneoxide quaternary ammonium compound alone or in admixture with a major or minor proportion of other quaternary ammonium compounds depends on the particular compounds involved. But in general the properties of quaternary ammonium compounds are such that bars can be made by melting and setting the components. Again, plasticisers, lather improvers and hardening agents, for example, may be incorporated in the bars, as described below.

Generally the bars will include a hardening agent, but occasionally a polyethyleneoxide quaternary ammonium compound will require the use of a softening agent. Compounds that are useful as softening agents include amine oxides and sulphobetaines, both also lather improvers and C₄-C₉ alkyl trimethylammonium quaternary ammonium compounds. Examples of polyethyleneoxide quaternary ammonium compounds that are so hard that bars containing them generally need to be softened are:

where R₁ is isopropyl, R₂ is stearyl and m+n=50; and polyethylene glycol (M. Wt. 1000):

Often when one component, for example a polyethyleneoxide quaternary ammonium compound, has a low melting point and tends to make a bar too soft, its effect can be counterbalanced by the use of another component whose hardening effect would otherwise be normally too great. Examples of polyethyleneoxide quaternary ammonium compounds that are very soft are the compounds described in Examples 23, 30, 38, 41, 42, 43, 47, 49, 50, 51, 55, 61, 62, 63, 64 and 65 hereinafter, and

The mechanism of action of hardening agents is not clearly understood. But it is believed that most compounds are effective either because they are hard themselves or because they form a hard "complex" with polyethylene oxide quaternary ammonium compounds.

Examples of classes of compounds that are hardening agents because they are hard themselves include talc and polymeric materials, such as polyvinyl alcohol, in powder form. Examples of classes of compounds that are hardening agents because they apparently form a hard "complex" with at least some polyethyleneoxide quaternary ammonium compounds include alkali metal salts of C₁₂ to C₂₀ alkane sulphonic acids, C₁₂ to C₂₂ fatty acids and the alkali metal salts thereof, C₁₀ to C₂₂ alkyl succinic acids, C₁₄ to C₂₂ alkenyl succinic acids and C₉ to C₁₈ alkane-1,3,3-tricarboxylic acids.

It has been found that when a bar according to the invention contains a hardening agent the agent should preferably constitute from 2 to 20%, particularly preferably from 5 to 15%, by weight of the bar.

A number of classes of compounds are particularly and surprisingly effective hardening agents. Such classes are as follows.

(A) Quaternary ammonium compounds not containing a polyethyleneoxide group and which contain at least one alkyl group containing from 12 to 22 carbon atoms in a straight chain. Preferred compounds have the general formulae:

and

where R and at least one of R₁ and R₂ are alkyl groups containing from 12 to 22 carbon atoms in a straight-chain, any group R₁ or R₂ not being such an alkyl group being an alkyl group containing from 1 to 12 carbon atoms, and X⁻ is a compatible anion as discussed above:

(B) Carboxylic acids containing from 12 to 22 carbon atoms in a straight chain. This is surprising since such fatty acids are softening agents when used in toilet bars based on soap;

(C) Ethyleneoxide condensates of alcohols containing from 12 to 20 carbon atoms in a straight chain, which contain from 20 to 40 ethyleneoxide units per molecule;

(D) Polyethylene glycols with molecular weights from 1,000 to 6,000; and

(E) Alkyl or alkenyl succinic acids in which the alkyl or alkenyl group contains from 10 to 18 carbon atoms in a straight-chain.

55 An important feature of a toilet bar is the lather obtained in use. The amount of lather produced by use of a bar varies considerably with the nature of the polyethyleneoxide quaternary ammonium compound used. As discussed below, lather from a bar can be improved, but a feature of the invention is the surprising discovery that for polyethyleneoxide quaternary ammonium compounds having a halide anion adequate lather is generally obtained if the value of K' is from 0 to 16, K' being defined by the expression:

$$K' = \frac{\sum C' - \sum (EO)}{\sum N^+}$$

70 where $\sum C'$ is the sum of the carbon atoms contained in linear alkyl chains containing more than 6 carbon atoms, $\sum (EO)$ is the total number of ethyleneoxide units and

$$\sum N^+$$

75 is the number of quaternary nitrogen atoms present.

This is not an invariable relationship but is a useful guide to the probable lathering characteristics of the polyethylene oxide quaternary ammonium compounds.

It is interesting that the condition is generally applicable to compounds containing, for instance, aryl, amide or ester groups; that is, hydrophobic groups other than alkyl chains containing more than 6 carbon atoms, and hydrophilic groups other than polyethyleneoxide groups do not materially affect the condition.

As mentioned above, lather improvers can be used in bars according to the invention. One feature of the invention is a toilet bar containing a polyethyleneoxide quaternary ammonium compound and a lather improver. A lather improver can act to increase the amount of lather a bar produces, to increase the quality, for example the creaminess, of the lather, or to provide lather when the bar otherwise would lather to a negligible extent.

It has been found that when a bar according to the invention contains a lather improver this should preferably constitute from 2 to 20%, particularly preferably from 5 to 15%, by weight of the bar.

Table I lists classes of compounds that can be used as lather improvers in bars according to the invention.

TABLE I

- (1) alkali metal salts of C_8 to C_{12} fatty acids;
- (2) alkali metal salts of C_8 to C_{12} alkyl sulphates;
- (3) ethanolamides of C_{12} to C_{18} fatty acids;
- (4) ethylene oxide condensates of ethanolamides of C_{12} to C_{18} fatty acids (up to 25 EO content);
- (5) C_8 – C_{18} alcohol ethoxylates (from 3 EO to 20 EO for C_8 – C_{12} , and from 5 EO to 25 EO for C_{13} – C_{18} alkyl groups);
- (6) alkali metal hydroxyalkylmethyltaurides, of the general formula

where R is a C_{10} to C_{16} alkyl group and M is an alkali metal cation;

(7) sulphobetaines of the general formula

where R is a C_{12} to C_{18} alkyl group;

- (8) alkali metal C_1 to C_6 alkylbenzene sulphonates;
- (9) C_8 to C_{12} fatty acids;
- (10) C_8 to C_{18} alkyltrimethylamine oxides;
- (11) C_{12} to C_{18} alkylbenzene sulphonamides;
- (12) polyethyleneglycols (M. Wt. 600 to 1500);
- (13) quaternary ammonium compounds not containing a polyethyleneoxide group, e.g. of the general formulae:

and

TABLE II

Example	Wt. (g.) tallow alcohol— $\overline{14}$ EO— $CH_2\cdot CH(OH)\cdot CH_2\cdot Cl$	Tertiary amine	Wt. tertiary amine	Solvent	Reflux time hours	Percent quaternary ammonium compound in solid	K value
2-----	50	Pyridine-----	20	None-----	144	76	0.54
3-----	64	N,N-dimethyldodecylamine-----	17	n-Butanol-----	24	82	0.40
4-----	64	N,N-dimethyl-p-dodecylbenzylamine.	25	n-Butanol-----	60	89	0.33
5-----	64	N,N-diOctadecylmethylamine.	43	n-Butanol-----	90	72	0.24

¹ Excess pyridine was present.

The preferred lather improvers are the sulphobetaines (7), the amine oxides (10), particularly where R is a C_{10} to C_{14} alkyl group and the polyethylene glycols (12).

It has also been found that C_{14} to C_{16} carboxylic acids are particularly useful as additives in bars according to the invention since they reduce lather properties less than any other of the carboxylic acids that can be used as hardening agents.

The C_{12} straight-chain carboxylic acid is particularly useful since it acts both as a hardening agent and as a lather improver.

It has further been found that a toilet bar according to the invention lathers particularly well when the bar contains from 2 to 5% by weight of an alkaline earth metal salt of a C_{12} to C_{22} carboxylic acid, and the salt also acts as a hardening agent.

Examples of polyethyleneoxide quaternary ammonium compounds for use in bars according to the invention and of their preparation are given below. Most methods of preparation give polyethyleneoxide quaternary ammonium compounds not of 100% purity. The presence of minor amounts of impurities does not substantially affect the essential properties of the compounds and their usefulness in toilet bars according to the invention.

In all of the Examples parts and percentages are by weight except where otherwise indicated.

The preparation of novel compounds of the general formula:

where R is a mono-, di- or tri-valent ethoxylated linking group, R_1 , R_2 and R_3 are compatible quaternary nitrogen substituent groups, n is from 1 to 3 and X^- is a compatible anion, are illustrated in Examples 1 to 32. Compounds of this type in which R is a monovalent C_6 – C_{22} alkyl ether group are shown in Examples 1 to 5.

Example 1

92.5 g. of epichlorohydrin was added dropwise to 874 g. of tallow alcohol— $\overline{14}$ EO containing 2 ml. boron trifluoride etherate over 15 mins. at 90–95° C., and the mixture was stirred for one hour. 10 g. of alumina (100–200 mesh) was added, the mixture stirred for 15 mins. and the alumina filtered off. The product was tallow alcohol— $\overline{14}$ EO— $CH_2\cdot CH(OH)\cdot CH_2\cdot Cl$.

450 g. of tallow alcohol— $\overline{14}$ EO

prepared as above, and 168 g. of dimethyloctadecylamine were refluxed in 200 ml. of n-butanol for 21 hrs. The n-butanol was removed and the reaction product dissolved in 95% aqueous methanol, adjusted to pH 9 and extracted four times with 40–60° petroleum ether. The solid obtained after the aqueous methanol had been removed contained 89% of tallow alcohol— $\overline{14}$ EO

the K value of which is 0.34.

Table II gives a list of examples of compounds similarly prepared by the reaction of tallow alcohol— $\overline{14}$ EO $CH_2\cdot CH(OH)\cdot CH_2\cdot Cl$ with various tertiary amines.

Example 6

R_1 , R_2 and R_3 in the general formula (I) can be substituted and contain groups such as aryl, amino, etc. An example is: tallow alcohol

$-\overline{14}$ EO— $CH_2\cdot CH(OH)\cdot CH_2\overset{+}{N}(CH_3)_2\cdot CH_2\cdot CH_2\cdot CH_2\cdot NH\cdot CO\cdot C_{17}H_{35}Cl^-$. This is prepared in a similar manner to that exemplified in Example 1 except that 64 g. of tallow alcohol— $\overline{14}$ EO— $CH_2\cdot CH(OH)\cdot CH_2\cdot Cl$ is reacted at reflux for 42 hrs.

with 28 g. of N,N -dimethyl-3-octadecanoylaminopropylamine. The solid obtained contained 79% of the required polyethylenoxide quaternary ammonium compound, which had a K value of 0.32.

In the general formula (I), R can be varied to be poly-functional by, for example, the use of the reaction products of epichlorhydrin with polyethylene glycol (M. Wt. 1,000). This is prepared in a similar manner to tallow alcohol —14 EO— $CH_2CH(OH)CH_2Cl$ in Example 1, by reacting 1,000 g. of polyethylene glycol (M. Wt. 1,000) with 18.5 g. of epichlorhydrin in the presence of 3 ml. of boron trifluoride etherate. The chlorhydrin product obtained is designated A in Table IV. Other compounds containing a reactive hydrogen atom were similarly converted to their chlorhydrins designated B to L as set out, with weights involved, in Table III below.

TABLE III

Chlorhydrin	Active hydrogen compound	Grams of active hydrogen compound	Grams of epichlorhydrin
B	$HO(CH_2CH_2O)_nH$ (m. wt. 200)	200	185
C	$HO(CH_2CH_2O)_nH$ (m. wt. 600)	400	123
D	$HO(CH_2CH_2O)_nH$ (m. wt. 1,500)	300	74
E	$C_{17}H_{35}CO-O-5 EO$	252	46

¹ In all cases except Example 32 the solvent used was n-butanol; in Example 32 the solvent was 2-methoxyethanol.

² Per monomer unit.

Polyethylenoxide quaternary ammonium compounds derived from polyethylene glycols (m. wt. from 200 to 1500, i.e. about 4.5 to 34 EO) have been found to provide surprisingly good after-wash feel when used, at levels of 15 to 30% by weight of the bar, in toilet bars based on soap; i.e. sodium salts of straight-chain C_{12} to C_{22} fatty acids.

The related compounds made from ethoxylated polypropylene glycol (MW about 1000 to 3500 i.e. about 18 to 66 propylene glycol units) with a greater number of EO

units in the range from about 4 to 50 EO units are useful particularly in toilet bars according to the invention.

These compounds are novel and a further aspect of the present invention is therefore a compound of the general formula:

5 $A.(CH_2CH_2O)_zB,2X^-$ or $A.(EO)_m-(CH_2CH_2O)_y-(EO)_nB,2X^-$ where A and B are quaternary ammonium groups, z is from 4.5 to 34, y is from 18 to 60, m or n is at least 3 and $m+n=4$ to 50, and X^- is a compatible anion.

Such compounds as well as being useful for formulation into a bar according to the present invention are also useful as detergents and as antistatic agents for the textile and polymer industries.

15 Particular polyethylenoxide quaternary ammonium compounds based on polyethylene glycols that show this advantage are compounds of the general formula:

20 $O(CH_2O)_zCH_2CH(OH).CH_2NR_1R_2R_3,2X^-$ where R_1 , R_2 and R_3 are compatible quaternary nitrogen substituent groups, Z is 4.5 to 34 and X^- is a compatible anion.

25 Related compounds exemplified hereinafter and having the general formula:

30 where R_1 , R_2 , R_3 , z and X^- have the same significance as above, are also novel and of particular interest for use in bars according to the invention.

Polyethylenoxide quaternary ammonium compounds for use in bars according to the invention can also be prepared by so-called quaternisation of amine ethylene oxide condensates. Example 33 exemplifies such a prepa-

65 ration and Table V lists further Examples 34 to 60 made by analogous routes.

EXAMPLE 33

70 50 g. of stearylamine-50 EO and 5 g. of benzyl bromide were dissolved in 200 ml. of 20% aqueous isopropanol and heated at 60-70°C. for 20 hrs. The pH of the solution was kept above pH 8 by the addition of sodium carbonate solution. The water and isopropanol were removed. Excess benzyl bromide was removed by washing with 60-80° petroleum ether. Inorganic salts were sepa-

rated by filtering an ethyl acetate solution. After removal of the ethyl acetate the resulting solid contained 89% of the quaternary ammonium compound:

which had a K value of 2.0.

where R_1 is a compatible quaternary nitrogen substituent group, n is at least 2, x is from 3 to 40 and X^- is a compatible anion. In the preferred compounds of this type R_1 is a C_8-C_{22} alkyl group or the group:

5

where R' is a C_8-C_{22} alkyl group and y is from 3 to 40.

¹ Isopropanol.

² Random primary amine.

³ It was found that for a substantial proportion of the product only one N atom was quaternised; the percent quaternary ammonium compound produced was calculated on the basis of diquaternisation.

⁴ See the following formula:

The polyethylene oxide quaternary ammonium compounds prepared from triethanolamine are particularly interesting compounds for use according to this invention as they have humectant properties. These compounds are novel and have the general formula:

where R_1 is a compatible quaternary nitrogen substituent group, R is a C_8-C_{22} alkyl group or the group $-(\text{EO})_y$, R' is a C_8-C_{22} alkyl group or the group $-(\text{EO})_z$, x is at least 2, $x+y+z=3$ to 40, and X^- is a compatible anion. In the preferred compounds R_1 is a methyl, ethyl or benzyl group.

Polyethyleneoxide quaternary polyethyleneimine compounds are also particularly interesting compounds both for use in bars according to the invention and also in the detergent, textile and polymer industries as antistatic and softening agents. These compounds have the general formula:

Examples 44 and 46 made from this triethanolamine di-stearate-20 EO are the same compounds, but made under different conditions of reaction.

⁵ Dimethylformamide.

Polyethyleneoxide quaternary ammonium compounds for use in bars according to the invention can also be prepared by the ethoxylation of tertiary amines with catalysts as shown in Example 61.

EXAMPLE 61

N,N-dimethyl-N-³⁶ EO- p-dodecylbenzylammonium chloride was prepared as follows. Ethylene oxide was passed through 50 g. of isopropanol at 80-120° C. containing 50 g. of N,N-dimethyl-p-dodecylbenzylamine and 12.15 g. of 35% aq. w/w. hydrogen chloride until the required increase in weight had occurred. The product obtained after removal of solvent contained 96% of the required quaternary ammonium compound, which had a K value of 1.71.

Examples 62 to 65 in Table VI below illustrate the preparation of related compounds from N,N-dimethyl-octadecylamine and using a range of acid catalysts.

TABLE VI

Example	Catalyst	Amount used	Moles EO in product	K value
62	HCl	6.3 g., 35% aq.	51	2.55
63	H ₃ PO ₄	7.4 g., 85% aq.	40	2.0
64	H ₂ SO ₄	12.4 g., 50% aq.	46	2.3
65	CH ₃ COOH	3.8 g.	62	3.1

The polyethylene oxide quaternary ammonium compounds of Examples 63 to 65 have anions other than the usual halide anions. However, it should be noted that in these and all other quaternary ammonium compounds the anions can readily be changed if desired by conventional anion exchange techniques, either to change one halide for another, or to substitute a halide for a non-halide anion or vice versa.

Polyethyleneoxide quaternary ammonium compounds can be prepared by methods other than those described above. The following reaction routes are examples of the many other reaction routes that are possible:

1.

where R is the residue of a compound having a reactive hydrogen before ethoxylation, n is an integer of at least 3, R¹ is an alkyl or alkaryl group and X⁻ is a halide anion.

This reaction is described in Schick, Nonionic Surfactants, Vol. 1, p. 391 (Edward Arnold Publishers Ltd., 1967).

2.

where R is the residue of a compound having a reactive hydrogen before ethoxylation, R¹ is an alkyl group and n and X⁻ are the same as above.

EXAMPLE 66

The ability of polyethyleneoxide quaternary ammonium compounds to disperse lime soap scum was tested as follows:

A series of aqueous solutions containing 0.02, 0.05, 0.1, 0.2, 0.5, 1.0, 2.0 and 5.0 g./l. of each compound to be tested were prepared using deionised water.

A solution of 0.25 g. of sodium oleate in 50 cc. of deionised water was prepared. 5 cc. of the sodium oleate solution together with 10 cc. of hard water (1 litre contained 1.3 g. of CaCl₂·6H₂O and 0.3 g. of MgCl₂·6H₂O) were measured into 9 Nessler tubes. One tube was used as a blank. To this tube was added 20 cc. of deionised water. To each of the remaining tubes was added 20 cc. of one of the solutions of the compound.

The Nessler tubes were then placed in a water-bath at 50° C. for one hour. The highest concentration of compound which gave a clear solution to the eye was noted.

The scum dispersion index (SDI) is defined as a percentage equal to:

$$\frac{\text{Wt. compound to give clear solution in this test}}{\text{Wt. oleate in this test}} \times 100$$

Table VII gives results obtained with polyethyleneoxide quaternary ammonium compounds for use in bars according to the invention and with other quaternary ammonium compounds.

EXAMPLE 67

The compatibility with anionic detergents of some polyethylene oxide quaternary ammonium compounds according to the invention and some other quaternary ammonium compounds was tested as follows:

10 ml. of a 2% aqueous solution of the quaternary ammonium compound was mixed with 10 ml of a 2% aqueous solution of the anionic detergent and the cloudiness of the mixture graded:

Clear	1
Very slightly cloudy	2
Slightly cloudy	3
Cloudy	4
Very cloudy, milky	5

The results obtained are given in Table VIII.

² Commercially available from Armour Hess Chemical Company under the trade name Ethoquad 18/25.

The polyethylene oxide quaternary ammonium compounds give the better results.

All the polyethylene oxide quaternary ammonium compounds illustrated in Examples 1 to 65 can be formed into bars according to the invention.

Examples of particularly good bars according to the invention which incorporate major proportions of polyethylene oxide quaternary ammonium compounds are set out in Table IX below. All of the bars were made by melting the components together and pouring the melts into moulds made from aluminium foil. All melts set to solid bars within 24 hours, most within 2 hours.

¹ See the following formula:² See the following formula:(the $\text{C}_{12}\text{H}_{25}$ alkyl group is derived from coconut fatty acids.)³ See the following formula:⁴ See the following formula:The following Examples in Table X are of bars according to the invention based on various anionic detergent active compounds with minor amounts of polyethylene oxide quaternary ammonium compounds.

50

¹ The detergent bases were as follows:

A=80/20 mix of sodium soaps of fatty acid derived from tallow and nut oil.

B=50/50 mix of sodium soaps of fatty acid derived from tallow and nut oil together with 10% by weight of the mix of free fatty acid derived from the mix.

C=9/5 mix of sodium soaps of fatty acids derived from tallow and sodium nonanol sulphate (nonanol is a commercially available mixture of C_6 alcohols and consists of 90% 3,5,5-tri-methyl hexanol together with minor amounts of other branched chain nonanols).

D=60% Commercial coconut oil Igepon A; 25% Sodium soap from 80/20 tallow/nut oil; 5% Fatty acids derived from 80/20 tallow/nut oil; 10% Water.

E=60% Sodium soaps from 80/20 tallow/nut oil; 6% Fatty acids from 80/20 tallow/nut oil; 12.5% Sodium C_{12-13} alkyl sulphate; 12.5% Potassium C_{12-15} alkyl sulphate; 9% Water.

F=60% Commercial coconut oil Igepon A; 10% Sodium soap from 80/20 tallow/nut oil; 20% Stearic acid; 5% Coconut fatty acid; 5% Water.

G=25% Sodium C_{11-14} alkane sulphonate; 25% Sodium C_{15-18} alkane sulphonate; 50% Sodium C_{15-18} olefin sulphonate.

H=The toilet bars of Examples 189 to 196 which were based on mixtures of alkali metal alkane sulphonates and olefin sulphonates had particularly good lather properties. Suitable alternative mixtures of alkali metal alkane sulphonates and olefin sulphonates are described in our U.K. patent specification No. 1,171,616.

EXAMPLE 197

Bars made from the polyethyleneoxide quaternary ammonium compounds of Examples 1 to 65 and the bars of Examples 68 to 196 were tested for after-wash feel. A panel of skilled assessors was used. The procedure was as follows:

Each panel member washed his or her hands with a bar made from the detergent base A in Table X, and rinsed them thoroughly. The hands were then washed with the experimental bar. At each washing the panel member used his or her normal washing technique. After washing with the experimental bar and rinsing, the hands were dried with a hair-drier and the hands rubbed together to assess 75 the after-wash feel.

45

55

¹ The detergent bases were as follows:
A=80/20 mix of sodium soaps of fatty acid derived from tallow and nut oil.
B=50/50 mix of sodium soaps of fatty acid derived from tallow and nut oil together with 10% by weight of the mix of free fatty acid derived from the mix.
C=9/5 mix of sodium soaps of fatty acids derived from tallow and sodium nonanol sulphate (nonanol is a commercially available mixture of C_6 alcohols and consists of 90% 3,5,5-tri-methyl hexanol together with minor amounts of other branched chain nonanols).
D=60% Commercial coconut oil Igepon A; 25% Sodium soap from 80/20 tallow/nut oil; 5% Fatty acids derived from 80/20 tallow/nut oil; 10% Water.
E=60% Sodium soaps from 80/20 tallow/nut oil; 6% Fatty acids from 80/20 tallow/nut oil; 12.5% Sodium C_{12-13} alkyl sulphate; 12.5% Potassium C_{12-15} alkyl sulphate; 9% Water.
F=60% Commercial coconut oil Igepon A; 10% Sodium soap from 80/20 tallow/nut oil; 20% Stearic acid; 5% Coconut fatty acid; 5% Water.
G=25% Sodium C_{11-14} alkane sulphonate; 25% Sodium C_{15-18} alkane sulphonate; 50% Sodium C_{15-18} olefin sulphonate.

60

H=The toilet bars of Examples 189 to 196 which were based on mixtures of alkali metal alkane sulphonates and olefin sulphonates had particularly good lather properties. Suitable alternative mixtures of alkali metal alkane sulphonates and olefin sulphonates are described in our U.K. patent specification No. 1,171,616.

TABLE XII—Continued

Test No.	Compound	Relative irritancy
5		0.34
	As prepared in Example 34	
6		1.28
7		0.53
	As prepared in Example 61 but ethoxylated to a higher degree.	
8		0.98
	As prepared similarly to Example 43 but using benzyl bromide.	
9		0.44
	As prepared in Example 33.	
10		0.47
	Prepared similarly to Example 33 but using benzyl chloride.	
11		0.18
	As prepared in Example 46.	
12		0.19
	As prepared in Example 21.	
13		0.05
	z is about 23, as prepared in Example 13.	
14		0.84
	z is about 23, as prepared in Example 8.	

These results show that compounds of the general formula:

where R_1 is a C_8 to C_{18} alkyl group; R_2 is a methyl or benzyl group; R_3 is a methyl or (EO) group, n is at least 3 and X^- is a halide ion, are surprisingly mild, particularly in the case of compounds containing at least 20 (EO) units.

There is some indication from similar tests that solubility, EO content and molecular weight are significant. Thus, compounds of the general formula:

where R_1 and R_2 are C_3 to C_{13} alkyl groups and R_3 is a methyl or benzyl group, are less irritant (possibly because they are less soluble) than the analogous compounds where at least one methyl group has been replaced by a $(EO)_n$ group where n is at least 3.

The presence of higher fatty acyl groups (C_{12} – C_{22}) in the polyethylene oxide quaternary ammonium compounds also appears to make the compounds exceptionally mild, as illustrated by Tests 11, 12 and 13.

EXAMPLE 204

The polyethylene oxide quaternary ammonium compounds that are listed in Examples 1 to 65 and that have a halide ion were tested for lather characteristics, both quantity and quality. The following compounds displayed adequate lather properties or better:

Examples 2, 3, 4, 7, 8, 9, 11, 12, 14, 15, 17, 18, 19, 23, 25, 26, 27, 28, 29, 30, 31, 41, 42, 43, 57 and 58.

Of these only for Example 18 and 25 is the value of K' defined by the expression:

$$K' = \frac{\sum C' - \sum (EO)}{\sum N^+}$$

wherein $\Sigma C'$, $\Sigma (EO)$ and ΣN^+ are as defined hereinbefore, not within the range of from 0 to 16.

The remaining compounds tested all displayed poor lather properties. Of these for only seven, namely Examples 13, 21, 39, 44, 46, 48 and 54 is the value of K' within the range of 0 to 16. Some of these exceptions to the general rule relating lathering properties to the value of K' are thought to be due to impurities in the polyethylene oxide quaternary ammonium compounds.

EXAMPLES 205-210

Bars were prepared with the formulations shown in Table XIII below:

TABLE XIII

Example	Detergent base ¹	Percent	Polyethylene oxide quaternary ammonium compound	Percent
205	A	90	Example 8	10
206	A	90	Example 10	10
207	A	90	Example 30	10
208	G	90	Example 8	10
209	G	90	Example 10	10
210	G	90	Example 30	10

¹ Detergent bases as used in Table X.

These bars were compared with the bars of Examples 147, 148, 149, 194, 195 and 196 for after-wash feel by the procedure of Example 198.

Although the bars of Examples 205 to 210 showed some slight improvement in after-wash feel, the effect was very much slighter than that shown by the bars of Examples 147, 148, 149, 194, 195 and 196.

EXAMPLE 211

The bar of Example 89 was tested against a conventional soap bar (50/50/10 tallow soap/nut oil soap/free fatty acids derived from the tallow soap and nut oil soap) using a panel of 30 skilled assessors.

Each member washed his or her hands with the soap and then dried them. Then a laboratory technician washed one hand of the member with the soap bar and the other hand with the bar of Example 89. After both hands were dried the member assessed the after-wash feel of each hand, usually by rubbing the palm of the hand with the tips of the fingers of the other hand.

In the experiment 24 members preferred the after-wash feel from the bar of Example 89, 4 preferred that from the soap bar and 2 were undecided.

The procedure was repeated for the bar of Example 106 when excellent after-wash feel results were again obtained, 21 of the assessors preferring the bar containing the polyethyleneoxide compound to 4 preferring the soap bar and 5 having no preference.

EXAMPLE 212

The skin moisturising effect of three polyethylene oxide quaternary ammonium compounds according to the invention was determined by exposing portions of guinea pig foot-pad corneum to 20% w/w. aqueous solutions of the compounds for 4 hours at room temperature. Each portion of treated corneum was then equilibrated in an atmosphere of 90% relative humidity (RH) and then weighed, after which it was transferred to a dry atmosphere and after a period of re-equilibration the sample of corneum was weighed again. The difference in weight is a measure of the water-binding capacity of the corneum expressed as mg. of water bound per 100 mg. of dry corneum. A control experiment using distilled water was also conducted and the results are expressed in Table XIV below, each result being an average figure of at least 9 individual tests.

TABLE XIV

Example No.:	Water Bound at 90% RH (mg./100 mg. of corneum)
7	32.2
30	30.0
35	31.7
Control	22.7

These figures demonstrate a significant increase in the water-binding capacity of skin after treatment with aqueous solutions of the polyethylene oxide quaternary ammonium compounds.

EXAMPLE 213

To determine the protective effect on human skin of washing with aqueous solutions of polyethylene-oxide quaternary ammonium compounds, samples of human skin were treated by the following procedure in Table XV after being mounted in perspex cells over saline saturated tissues.

TABLE XV

25	Skin Sample	Treatment
A	Exposed to a 1% aqueous solution of the polyethylene oxide quaternary ammonium compound of Example 13 for 30 minutes*.	
B	Exposed to a 1% aqueous solution of the polyethylene oxide quaternary ammonium compound of Example 28 for 30 minutes*.	
C	Exposed to a 1% aqueous solution of sodium lauryl sulphate for 30 minutes*.	
D	Exposed to a 5% aqueous solution of sodium lauryl sulphate for 30 minutes*.	
E	Exposed to distilled water only for 30 minutes*.	
F	A small amount of the undiluted polyethylene oxide quaternary ammonium compound of Example 13 was rubbed into the skin using a Teflon rod for 15 sec. and left in contact in the skin for 10 minutes; after rinsing with distilled water for 2 minutes the skin was exposed to a 1% aqueous solution of sodium lauryl sulphate for 30 minutes*.	
G	The treatment was the same as for sample F except that a 5% aqueous solution of sodium lauryl sulphate was used.	
H	The treatment was the same as for sample F except that the polyethylene oxide quaternary ammonium compound was that of Example 28.	
I	The treatment was the same as for sample H except that a 5% aqueous solution of sodium lauryl sulphate was used.	

*The aqueous solution used was replaced with a fresh solution after 10 minutes and again after 20 minutes.

After the initial treatment, each of the skin samples was rinsed in three changes each of 2 minutes duration in distilled water and then "fixed" in 5% aqueous solution of glutaraldehyde buffered to pH 6.9 with phosphate for 3 hours at $-4^\circ C$. After fixation, the skin samples were thoroughly rinsed and then they were cooled rapidly in Freon 12 cooled to $-158^\circ C$. by liquid nitrogen. The skin samples were then transferred to a "Speedivac" tissue drier and freeze dried overnight. The dry samples of skin were then metal shadowed with gold/palladium for examination in a scanning electron microscope.

Observation of each of the skin samples in the scanning electron microscope showed that pre-treatment of the skin with either of the polyethylene oxide quaternary ammonium compounds according to the invention before exposure to the solution of sodium lauryl sulphate was beneficial in that the degree of surface damage to the skin was markedly reduced when compared with that obtained by treatment with solutions of sodium lauryl sulphate alone.

EXAMPLE 214

A polyethylene oxide quaternary ammonium compound containing ester linkages was prepared from polyethylene glycol as follows. 200 g. of polyethylene glycol (MW 1000) and 40 g. of chloracetic acid were dissolved in 300 ml. of toluene and refluxed for 24 hours. The water formed during the reaction was removed by azeotropic distillation and the solution allowed to stand over sodium carbonate

25

for one hour to remove chloracetic acid. The solution was filtered and the solvent distilled off to leave the compound:

where n is about 23.

115 g. of this compound and 59 g. of N,N-dimethyl hexadecyl amine were refluxed together in 300 ml. of ethyl acetate for 24 hours. The ethyl acetate was then removed and the reaction product was dissolved in 95% aqueous methanol and extracted with 40-60° petroleum ether. The resulting solid contained 72% of the compound:

where n is about 23. The K value for this compound is 0.58.

A toilet bar was prepared from this polyethylene oxide quaternary ammonium compound and was found to have good lather and after-wash feel properties.

What is claimed is:

1. A toilet bar containing from 15 percent to 100 percent by weight of a polyethylene oxide quaternary ammonium compound or compounds containing a polyethylene oxide group with at least three ethyleneoxide units in a chain, which polyethyleneoxide quaternary ammonium compound is selected from the group consisting of detergents polyethyleneoxide quaternary ammonium compounds having K values of from 3 to 0.01 and non-detergents polyethyleneoxide quaternary ammonium compounds having K values of from 30 to 0.67, the K value being defined by the expression:

$$K = \frac{\Sigma (\text{EO})}{\Sigma C \times \Sigma N^+}$$

where $\Sigma (\text{EO})$ is the total number of ethyleneoxide units, ΣC is the total number of carbon atoms not in ethyleneoxide units and ΣN^+ is the total number of quaternary nitrogen atoms per repeating unit of the compound, and up to 20 percent by weight of a hardening agent selected from the group consisting of compounds of the general formula:

where R_1 is a C_{12} to C_{22} straight-chain alkyl group, R_2 is a methyl group or C_{12} to C_{22} straight-chain alkyl group and X^- is a compatible anion, C_{12} to C_{22} straight-chain carboxylic acids, compounds of the general formula:

where R is a C_{12} to C_{20} straight-chain alkyl group and n is from 20 to 40, polyethylene glycols with a molecular weight from 1,000 to 6,000 alkyl and alkenyl succinic acids of the general formula:

where R is a C_{10} to C_{18} straight-chain alkyl or alkenyl group; and up to 20 percent by weight of a lather improver selected from the group consisting of alkali metal salts of C_8 to C_{12} fatty acids, alkali metal salts of C_8 to C_{12} alkyl sulphates, ethanolamides of C_{12} to C_{18} fatty acids, ethyleneoxide condensates of ethanolamides of C_{12} to C_{18} fatty acids with up to 25 EO groups, C_8 to C_{12} alcohol ethoxylates containing 3-20 EO groups, C_{12} to C_{18} alcohol ethoxylates containing 5-25 EO groups, alkali metal hydroxyalkylmethyl taurides of the general formula:

where R is a C_{10} to C_{16} alkyl group and M is an alkali metal cation, sulphobetaines of the general formula:

where R is a C_{12} to C_{18} alkyl group, alkali metal C_1 to C_6 alkyl benzene sulphonates, C_8 to C_{12} fatty acids, C_8 to 75

26

C_{18} alkyl dimethyl amine oxides, C_{12} to C_{18} alkyl benzene sulphonamides, quaternary ammonium compounds of the general formula:

5 where R is C_8 to C_{18} and quaternary ammonium compounds of the general formula:

10 where R is C_{12} to C_{18} , and polyethylene glycols with a molecular weight from 600 to 1,500; and up to 85 percent by weight of an anionic detergent active compound.

2. A bar as claimed in claim 1 in which the polyethyleneoxide quaternary ammonium compound has the general formula

where R_1 is a C_8 to C_{18} straight-chain alkyl group or a C_8 to C_{18} straight-chain alkyl group interrupted by a phenylene group, R_2 is a methyl or benzyl group, R_3 is a methyl or polyethyleneoxide group and n is at least 3.

3. A bar as claimed in claim 1 containing at least 50% by weight of a polyethyleneoxide quaternary ammonium compound which contains at least one C_8 to C_{18} straight-chain alkyl group and which contains no more than 40 ethyleneoxide units per quaternary nitrogen atom.

4. A bar as claimed in claim 1 containing from 2 to 20% by weight of a hardening agent.

5. A bar as claimed in claim 4 containing from 5 to 30% by weight of a hardening agent.

6. A bar as claimed in claim 1 containing from 2 to 20% by weight of a lather improver.

7. A bar according to claim 6 containing from 5 to 15% by weight of a lather improver.

8. A bar as claimed in claim 1 in which the lather improver is a C_{12} straight-chain carboxylic acid.

9. A bar as claimed in claim 1 containing from 2 to 5% by weight of an alkaline earth metal salt of a C_{12} to C_{22} straight-chain carboxylic acid.

10. A bar as claimed in claim 1 comprising a major proportion of a polyethyleneoxide quaternary ammonium compound having detergents properties.

11. A bar as claimed in claim 1 based on an anionic detergent active compound and containing from 15 to 45% by weight of a polyethyleneoxide quaternary ammonium compound.

12. A bar as claimed in claim 11 containing from 20 to 30% by weight of a polyethyleneoxide quaternary ammonium compound.

13. A bar as claimed in claim 11 in which the anionic detergent active compound is soap.

14. A bar as claimed in claim 11 in which the anionic detergent active compound is a mixture of alkali metal alkane sulphonates and olefin sulphonates.

15. A bar according to claim 1 wherein the polyethyleneoxide quaternary ammonium compound contains a higher fatty acyl group.

16. A bar according to claim 1 wherein the polyethyleneoxide quaternary ammonium compound has the general formula:

where R_1 , R_2 and R_3 are compatible quaternary ammonium substituent groups, X is a compatible anion and n is an integer of from 1 to 3, and, when n is 1, R is selected from the group consisting of

where x is from 3 to 40, when n is 2, R is

where x or y is at least 3 and $x+y=4$ to 40 and when n is 3, R is selected from the group consisting of

and

where R' is a compatible quaternary ammonium substituent group, and x, y or z is at least 3 and $x+y+z=5$ to 40.

17. A bar according to claim 16 wherein the polyethyleneoxide quaternary ammonium compound has the general formula:

where R_1, R_2 and R_3 are compatible quaternary ammonium substituent groups, x is from 3 to 40, and X^- is a compatible anion.

18. A bar according to claim 1 wherein the polyethyleneoxide quaternary ammonium compound has the general formula:

where

are quaternary ammonium groups, z is from $\overline{4.5}$ to $\overline{34}$, y is from $\overline{18}$ to $\overline{60}$, m or n is at least 3 and $m+n$ is from 4 to 50, and X^- is a compatible anion.

19. A bar as claimed in claim 18 wherein the polyethyleneoxide quaternary ammonium compound has the formula:

20. A bar according to claim 18 wherein the polyethyleneoxide quaternary ammonium compound has the formula:

21. A bar as claimed in claim 18 wherein the polyethyleneoxide quaternary ammonium compound has the formula:

5 where R_1, R_2 and R_3 are compatible quaternary nitrogen substituent groups, y is from $\overline{18}$ to $\overline{60}$, m or n is at least 3 and $m+n$ is 4 to 50, and X^- is a compatible anion.

10 22. A bar according to claim 1 wherein the polyethyleneoxide quaternary ammonium compound has the general formula:

15 where R_1 is a compatible quaternary nitrogen substituent group, R is a C_6-C_{22} alkyl group or the group $-(\text{EO})_y$, R' is a C_6-C_{22} alkyl group or the group $-(\text{EO})_z$, x is at least 2, $x+y+z=3$ to 40 and X^- is a compatible anion.

20 23. A bar according to claim 12 where R_1 is methyl, ethyl or benzyl group.

25 24. A bar according to claim 1 wherein the polyethyleneoxide quaternary ammonium compound is a polyethyleneimine which has the general formula:

30 where R_1 is a compatible quaternary nitrogen substituent group, x is 1 or from 3 to 40, x only being 1 where R_1 contains the group $-(\text{EO})_y$ where y is from 3 to 40, n is at least 12 and X^- is a compatible anion.

35 25. A bar according to claim 24, wherein R_1 is a C_6-C_{22} alkyl group or the group:

40 40 where R' is a C_6-C_{22} alkyl group and y is from 3 to 40.
